UNITED STATES PATENT OFFICE.

ERNST G. HELANDER, OF YOUNGSTOWN, OHIO.

CONDENSER.

1,319,647.

Specification of Letters Patent.

Patented Oct. 21, 1919.

Application filed April 19, 1917. Serial No. 163,175.

To all whom it may concern:

Be it known that I, ERNST G. HELANDER, a citizen of the United States, residing at Youngstown, Mahoning county, Ohio, have 5 invented a new and useful Improvement in Condensers, of which the following is a full, clear, and exact description, reference being had to the accompanying drawings, forming part of this specification, in which—

10 Figure 1 is a vertical section of a condenser embodying my invention, and

Figs. 2 and 3 are transverse sections, taken, respectively, on the lines II—II and III—III of Fig. 1.

15 My invention has relation to improvements in condensers, and more particularly to jet condensers of the counter-current type.

The object of my invention is to provide a condenser having means whereby the largest possible area of water surface will be exposed to the action of the incoming steam, while at the same time permitting a maximum volume of cooling water to be used economically in a condenser of a given size.

20 25 The nature of my invention will be best understood by reference to the accompanying drawings in which I have shown a preferred embodiment thereof, and which will now be described, it being premised, however, that various changes can be made in the details of construction, arrangement and combination of the parts without departing from the spirit and scope of my invention as defined in the appended claims.

30 35 In these drawings the numeral 2 designates the main condensing chamber having the steam inlet pipe 3, the water supply pipe 4, and pipe connection 5 leading to an air pump or other suction apparatus, in the usual manner. 6 indicates the tail pipe.

40 45 Placed below the discharge opening of the water inlet pipe 4 is a baffle consisting of a horizontal portion 7 and a vertical portion 8 at the farther end of the horizontal portion, there being a free space or passage 9 between the outer wall of the chamber 2 and said vertical portion 8. The horizontal portion 7 has formed therein a plurality of water distributing slots 10 which are arranged in fan-like form, being separated from each other by greater distances at the ends thereof adjacent to the water inlet than at the opposite ends. 11 designates a second baffle placed above the steam inlet connection 3 and also consisting of a horizontal and a vertical portion, there being a free

space or passage 12 between the vertical portion and the outer wall of the condenser. The horizontal portion of the baffle 11 is also formed with a plurality of through slots 13 arranged in fan-like form, but reversely to the slots 10. That is to say, the slots 13 are separated by greater distances at the ends adjacent to the steam inlet than at their opposite ends, the steam inlet being shown as being at the opposite side of the condenser from the water inlet. The baffle 11 is also provided with the oblique downwardly and inwardly extending deflector projection 14 which is in the path of a portion of the incoming steam.

In the water distributing arrangements heretofore generally in use in condensers of this type, the water falls in the form of a cone whose surface is exposed to the action of the incoming steam. Such a cone does not expose a very large surface of water, and the steam that is not immediately condensed has to force its way upward to meet the falling water at a higher level. This has a tendency to limit the amount of water that may be used to advantage in the condenser, since if the water falls in a compact mass the steam cannot readily work its way through. By my improved distributing arrangement, I at once expose the largest possible surface of water to the incoming steam which is deflected downwardly by the projection 14. By reason of the fan-like arrangement of the water distributing slots, very little resistance is offered to the incoming steam at the first contact, after which the distances or open spaces between the slots becomes contracted, thereby acting to force the particles of steam close up to the falling sheets of water before the water reaches the free passage 12. The uncondensed steam and uncondensable vapor passes upward through the passage 12 and again meets the upper series of falling sheets of water from the slots 10. The residue passes upwardly through the passage 9 and thence to the air outtake. As the steam passes underneath the upper baffle 7 it again at first meets with a minimum of resistance, due to the greater distance separating the upper series of slots 10 at that side of the condenser; but as it passes toward the passage 9 there is a further action tending to force the particles of steam closely between the falling sheets of water before the steam can escape said passage 9.

My invention very greatly increases the efficiency of the condenser and provides a simple construction by which a maximum amount of cooling water can be run through a condenser of a given diameter, thus decreasing the size and cost of the condensing vessel required. I have also found that there is practically no loss in vacuum between the part of the condenser where the air enters and the top where the air is taken off. Friction losses in the condenser are also small. The vertical portions of the water distributers provide means whereby water may collect on the distributers to a sufficient depth to form a proper head for forcing the cooling water through the slots.

I claim:

1. A counter-current condenser, having a steam inlet pipe which enters the condenser vessel horizontally, and also having a combined baffle and water container forming in effect a continuation within the vessel of the upper wall of said pipe, said baffle and container having an upturned free edge at the side opposite the steam inlet, and also having a plurality of water-distributing slots which converge toward each other in a fan-like arrangement in a direction away from the steam inlet pipe, there being a free upward passage between the up-turned edge of the baffle and the adjacent wall of the condenser vessel, the condenser also having another similar baffle above the first-named one and placed oppositely thereto so that its distributing slots converge toward, and the upward passage at its edge is at, the opposite side of the vessel, substantially as described.

2. A counter-current jet condenser having a water inlet pipe, a baffle below the discharge of said pipe, said baffle having a plurality of distributing slots which diverge from each other toward the ends thereof nearest the discharge of the water inlet, and also having a steam inlet connection and a water distributing baffle above said inlet, said baffle having therein a plurality of slots which diverge toward the steam inlet, said baffles projecting from opposite sides of the condenser chamber, and there being a free space between one end only of each baffle and the adjacent wall of said chamber, substantially as described.

3. A counter-current jet condenser having a water inlet pipe, a baffle below the discharge of said pipe, said baffle having a plurality of distributing slots which diverge from each other toward the ends thereof nearest the discharge of the water inlet, and also having a steam inlet connection and a water distributing baffle above said inlet, said baffle having therein a plurality of slots which diverge toward the steam inlet and in the opposite direction to the divergence of the slots in the first named baffle, each of said baffles having a vertical water-retaining portion at its end, and there being a free passage between each such portion and the adjacent wall of the condenser chamber, substantially as described.

In testimony whereof, I have hereunto set my hand.

ERNST G. HELANDER.
